UNITED STATES PATENT OFFICE.

FREDERICK RICHARDSON, OF PROVIDENCE, RHODE ISLAND.

HEEL-PLATE FOR RUBBER BOOTS AND SHOES.

SPECIFICATION forming part of Letters Patent No. 270,911, dated January 23, 1883.

Application filed April 1, 1882. (No model.)

To all whom it may concern:

Be it known that I, FREDERICK RICHARDSON, of the city and county of Providence, and State of Rhode Island, have invented a new and useful Improvement in Rubber Boots and Shoes; and I do hereby declare that the following is a full, clear, and exact description of the same, reference being had to the accompanying drawings, forming part of this specification.

This invention has reference to a metallic wearing plate or tap for the heels of rubber boots and shoes; and it consists in a metal heel plate or tap formed of a lattice-work or arrangement of intersecting cross-bars inclosed by a rim of suitable shape, the spaces between the cross-bars being wider at the bottom than at the top and filled with rubber, substantially as and for the purpose hereinafter particularly described, the whole being adapted to be secured to the heel portion of a rubber boot or shoe.

Figure 1 is a perspective view of a rubber shoe the heel of which is protected by a metal wearing-surface formed of narrow bars interlaced so as to leave openings into which rubber is pressed, so that the whole can be secured to the shoe by cementation. Fig. 2 is a view of the metallic wearing-surface. Fig. 3 is a sectional view of the heel portion of a rubber shoe through the line x. Fig. 4 is a sectional view of a portion of the metal wearing-surface.

The object of this invention is to protect the heel of a rubber boot or shoe with metal, so as to increase the durability of rubber boots and shoes, particularly the heel portion of the same.

In the drawings, A represents the rubber sole of a boot or shoe, and B a metal wearing-surface consisting of a rim and intersecting bars, which form an open lattice-work, into the spaces between the bars of which rubber is secured.

c is the rim, and d d are the bars. The rim and the bars are made tapering in section, so that the spaces between the bars form dovetailed blocks, into which rubber is pressed, which, when secured to the sole by cement, will firmly hold the latticed metal wearing-surface.

The upper edge of the bars d d may be made with a slightly-raised edge, as is shown in Figs. 3 and 4; or the upper edge may be made

flush with the rubber, so that a smooth surface 55 is presented.

The bars d d may be made with a knife-edge or nearly a knife-edge at the lower wearing-surface, so that the metal lattice-work can be forced into a sheet of rubber and all the 60 spaces filled with the same. When the heel is thus prepared it is secured to the sole by cement, by which the dovetailed rubber pieces in the lattice-work will be firmly secured to the sole, and thus the metal wearing-surface 65 is firmly held and a durable heel secured.

The rubber filling the spaces formed by the lattice-work metal yields to the pressure in walking and prevents slipping, while the metal protects the rubber and increases the durability of the boot or shoe.

By the peculiar construction of a latticed heel-surface the interstices of which are filled with rubber a firm hold of the heel is secured, as the rubber will yield to the irregularities of the surface and prevent slipping, while the metal protects the rubber against wear.

One peculiarity and advantage of this construction of heel consists in the anti-balling 80 quality of this heel when used in snow, as the compressible rubber fills the spaces between the metal lattice-work. The weight of the wearer breaks up at each step the snow that is forming on the heel by the rubber filling the 85 spaces between the ribs yielding when the weight is exerted, and the metal ribs cut up any adhering snow. When the heel is raised the rubber in the spaces between the ribs d d acts as a plunger and forces the snow off from 90 the metal ribs or lattice-work.

The spaces between the ribs d d may be made larger than here shown, so that less metal is required in the heel.

Having thus described my invention, I claim 95 as new and desire to secure by Letters Patent—

A tap for the heels of rubber boots and shoes, consisting of the rim c and cross-bars d d, the spaces between which are wider at the bottom than at the top and are filled with 100 rubber, the whole arranged to be secured to the heel portion of the boot or shoe, as described.

FREDERICK RICHARDSON.
